UNITED STATES PATENT OFFICE.

THOMAS FERRY, OF WILMINGTON, DELAWARE.

DESIGN FOR A SUSPENDER MEMBER OR BAND.

SPECIFICATION forming part of Design No. 34,993, dated August 27, 1901.

Application filed January 19, 1900. Serial No. 2,073. Term of patent 14 years.

To all whom it may concern:

Be it known that I, THOMAS FERRY, of Wilmington, in the county of Newcastle, and in the State of Delaware, have invented and produced a certain new and original Design for a Suspender Member or Band; and I do hereby declare that the following is a full, clear, and exact description thereof, reference being had to the accompanying drawings, in which—
10 Figures 1 and 2 are plan views of a suspender member or band embodying my design, showing, respectively, the obverse and reverse sides thereof.

The object of my invention is to provide a new and original shape for the main member or band of the suspender; and to this end said invention consists in the design for a suspender member or band, substantially as herein shown and described.

20 My design consists of the member or band shown, it comprising a strip consisting of two straight portions A and B, the portion A be-

ing comparatively short and oblique to the portion B, a series of holes C and C being formed at intervals along the portion A at 25 the opposite end of the strip and mid-length of the strip and the strip adjacent to each series of holes having a continuous portion of its surface differing in appearance from other portions of the strip-surface, the continuous 30 portion of differently-appearing surface extending in the case of that of the strip part A over the adjacent surface of the part B.

Having thus described my invention, what I claim is—

35 The design for a suspender member or band, substantially as herein shown and described.

In testimony that I claim the foregoing I have hereunto set my hand this 11th day of January, A. D. 1900.

THOMAS FERRY.
